UNITED STATES PATENT OFFICE.

EMBURY McLEAN, OF BROOKLYN, NEW YORK.

FURNACE CONTROL.

1,355,157.

Specification of Letters Patent. Patented Oct. 12, 1920.

Application filed January 7, 1918. Serial No. 210,747.

To all whom it may concern:

Be it known that I, EMBURY McLEAN, a citizen of the United States, and a resident of New York city, borough of Brooklyn, in the county of Kings and State of New York, have invented certain new and useful Improvements in Furnace Control, of which the following is a specification.

My invention relates to new and useful improvements in furnace control and more particularly relates to a method and means for automatically controlling the operation of a fuel feeding means for feeding fuel to the furnace of a boiler. The invention contemplates an improved method and means for automatically varying the operation of the fuel feeding means to vary the rate or quantity of feed of the fuel to the furnace, so as to maintain the proper supply of fuel, for example in the case of an automatic stoker the proper thickness or resistance of the fuel bed, in accordance with the amount of draft supplied, or in accordance with the thickness or resistance of the fuel bed.

The invention is particularly adapted for use in connection with a boiler furnace having an automatic stoker, and which is supplied with draft from a blower or other air impelling means, the speed of which may vary or remain constant, and I particularly contemplate the application of the invention to a boiler furnace furnished with a blower delivering air to the ash pit beneath the fire bed, and in which means, such for example as disclosed in my Letters Patent No. 1,071,771, dated September 2, 1913, is provided for maintaining constant the fire box pressure for varying rates of combustion—in accordance with the principle set forth in my prior Patent No. 826,349, July 17, 1906. I am aware of the fact that means have previously been provided for automatically varying the speed of the stoker in order to increase or decrease the quantity of fuel delivered which result was accomplished by mechanism acting in accordance with variations of steam pressure in the boilers, or of ash pit air pressure. The first of these methods, that is, control of the fuel feed by the steam pressure, is objectionable because variations in condition of the fuel bed may take place due to unavoidable dif-

ferences in the qualities or condition of the fuel to which the steam pressure does not respond as the controlling medium, and the second method, that is, control of the fuel feed by the ash-pit air pressure, is objectionable because under certain conditions the operation performed is just the reverse of the one desired—for instance, a reduction of pressure in the ash pit acts to slow up the feed of the stoker when in fact an increase of speed of feed is desirable. In my invention I overcome both of the objections stated and am able to vary the speed of the stoker and the consequent rate of feed of the fuel whenever there is such a variation in the relation between the fuel bed and the draft that the fuel bed does not offer sufficient resistance to the draft, or offers too great resistance to the draft, which may be due either to changes in condition of the fire bed, or changes in the speed of the blower.

In other words, in practising my invention, when employing an automatic stoker, a definite relation is maintained between the speed of the stoker or rate of feed of fuel, and the speed of the blower or supply of air to the furnace at all times so long as the resistance of the fuel bed remains normal. If the resistance of the fuel bed is less than normal the relative speed of the stoker is increased, and if the resistance of the fuel bed is greater than normal the relative speed of the stoker is decreased until the normal condition of the fuel bed is attained, or until the resistance of the fuel bed is such that the rate of fuel feed is equal to the rate of fuel consumption.

The invention consists in the improvements to be more fully described hereinafter and the novelty of which will be particularly pointed out and distinctly claimed.

I have fully and clearly illustrated my invention in the accompanying drawings to be taken as a part of this specification, and in which—

Figure 1 is a view in side elevation, partly in section, of a preferred embodiment of my invention, certain of the parts being shown enlarged in order that the construction and operation thereof will be clear.

Fig. 2 is a view in front elevation, and partly in section, of a pressure regulator for

controlling the flue damper of the boiler to maintain the pressure of gases in the furnace substantially uniform, and to control the feed of the stoker.

5 Fig. 3 is a section through the furnace wall showing the pressure regulator of Fig. 2 in vertical transverse section.

10 Fig. 4 is a view in front elevation of means for regulating the extent of movement of the stoker engine valve in order to bear a desired relation to the speed of the blower and the position of the flue damper.

Fig. 5 is a transverse section on the line 5-5 of Fig. 4.

15 Fig. 6 is a detail of the governor valve for the stoker engine.

Fig. 7 is a view in side elevation partly in section of an alternative arrangement.

Referring to the drawings by characters 20 of reference, 1 designates a boiler for the generation of steam, and 2 is a furnace of any suitable type for heating the boiler. The furnace is fed with fuel by a stoker 3, including a hopper 4 and suitable feeding 25 means driven by a power shaft 5 carrying a pulley 6 connected by a driving belt 7 with a driving pulley 8 on the shaft of a steam engine 9 driven and controlled in a manner to be presently described.

30 I desire it understood that my invention is not limited to the particular type of stoker shown and described, inasmuch as the invention is applicable to other types of stokers without departing from the spirit 35 and scope thereof. The stoker shown is of the type generally known in the art as a "Taylor" stoker.

10 designates a flue outlet from the furnace chamber the same being controlled by 40 a plate damper 11 mounted on a pivot 12, said plate damper being movable in order to vary the outlet area of the flue. Mounted on the pivot of the damper is a lever 13 connected by a flexible connection 14 with 45 the piston rod 15 of the piston 16, slidably arranged within an operating cylinder 17 adapted to contain a fluid for moving and controlling the said piston to vary the position of the damper in the outlet flue. The 50 upper end of the cylinder 17 is connected by a pipe 18 with a feed pipe 19 leading to any suitable source of fluid under pressure, for example, oil, water, air, or any pressure medium which will operate to move 55 the piston. This pipe 19 is connected to a port 20 opening into a pilot valve chamber 21, said chamber being also connected by port 22 with a pipe 23 leading to the lower end of the cylinder 17. It will be noted 60 that the pipes 18 and 23 open into the cylinder 17 on opposite sides of the piston 16. Leading from the pilot valve chamber 21 is a vent 24. Within the chamber 21 is a pilot valve 25 connected at its upper end

by a rod 26 to an arm 27 rigidly mounted 65 on a regulator plate 28, pivoted as at 29 in a casing 30, open on one side to the interior of the furnace through the flue duct 31, and to the outside atmosphere on the other side through the open bottom 32 of the 70 casing 30. The pivot 29 is preferably located at approximately the center of gravity of the plate 28 or in a position such that the movement of the plate will not be affected by the action of gravity. The plate 75 may be provided with a depending weight 33 in order to provide for the balancing of the plate so that its movements will not be affected by the action of gravity. Mounted on the casing is an arm 34, to which are 80 connected the ends of oppositely disposed springs 35, 36, connected to an arm 27 rigid with the plate 28 and operating to return the latter to a neutral position, for example as shown in Fig. 3, when the pressure is 85 the same on both sides of said plate, or when the desired difference in pressure is maintained. The pilot valve 25 is so connected to the plate that when the latter is moved by a preponderance of atmospheric 90 pressure over furnace pressure, said valve will uncover the said port 22 so that the latter will be connected with the vent 24, permitting the fluid in the cylinder 17 beneath the piston 16 to flow out of the cylinder. When the valve is in the position just 95 described and there is no pressure below the piston the pressure medium from the supply pipe 19 which at all times acts on the upper side of the piston flows through the 100 pipe 18 into the cylinder 17 above the piston 16, and moves the latter downward to cause the plate damper to be swung on its pivot and reduce the outlet area of the flue. When the regulator plate 28 is moved 105 by a preponderance of the furnace gas pressure, plus the power of the spring 36, in excess of the atmosphere pressure, the sliding valve is moved down to a position to 110 cut off communication between the port 22 and the vent 24, and to establish communication between said port 22 and the supply pipe 19, whereby the pressure medium is 115 permitted to flow from the pipe 19 through the pilot valve chamber and the pipe 23 to the cylinder 17 beneath the piston 16. In view of the fact that the exposed area on the under side of the piston 16 is greater than the exposed area on the upper side of 120 said piston, said piston will be moved upward to permit the weight 12^a on the plate damper pivot 12 to swing the plate damper to a position to enlarge the outlet area of the flue.

Air under pressure is supplied to the furnace under the fuel bed by means of a blower 37, delivering the air into a duct 38 opening as at 39 under the fuel bed of

the furnace. This blower may be driven by a steam engine, or other motor, 40, fed with steam from the boiler through a feed pipe 41, controlled by a valve 42, preferably in the form of a rotary valve having a transverse port 43, and carrying on one end a weighted lever 44. The operation of this valve is controlled by automatic means controlled and actuated by the steam pressure of the boiler, which means will now be described.

45 designates a diaphragm chamber containing a diaphragm 46 exposed on its under face to steam pressure from the boiler admitted to a diaphragm chamber through a feed pipe 47 connected to the boiler. Connected to the upper face of the diaphragm 46 is a thrust rod 48 carrying at its upper end a knife-edge fulcrum 49, upon which 20 rests a lever 50 fulcrumed at one end on the diaphragm casing, as at 51, and carrying at its free end fixed weights 52, and at an intermediate point an adjustable slide weight 53. Arranged above the diaphragm chamber is a 25 piston cylinder 54 containing a slide piston 55, connected to a piston rod 56, which at its upper end is connected to a flexible connection 57 passing over guide pulleys 58 and connected to the said valve lever 44, as shown 30 at 59. The cylinder 54 is adapted to receive a suitable fluid under pressure in order to control and actuate the piston 55, the flow of the pressure medium to and from said cylinder being controlled by a pilot valve, 35 which I will now describe.

60 is a valve casing containing a valve chamber 61 connected by ports 62, 63, with the cylinder 54, and opening on opposite sides of the said piston 55. In the valve 40 chamber 61 is a double slide valve carrying valve heads 64, 65, mounted on a valve rod 66, said valve operating to control the inlet and outflow of the pressure medium through the said ports 62 and 63. In Fig. 1 the said 45 valves are shown in a neutral position, closing both said ports. Fluid under pressure is fed from any suitable source to the valve chamber 61 at a point intermediate the said valve heads through a pipe 67, and said 50 chamber is provided with vents 68, 69, located respectively above the valve head 64 and below the valve head 65, the arrangement being such that when the valve heads 64 and 65 are simultaneously moved the 55 ports 62 and 63 may be alternately connected with the supply 67 to the cylinder, and with one or the other of the vents 68, 69. The lever 50 is connected by a rod 70 to an intermediate point on the link member 71, the 60 opposite ends of which are pivoted loosely or by a slotted joint to the rod 66, as at 72, and as at 73 also by a loose joint to one end of the lever 74, which is fulcrumed at an intermediate point 75. The opposite end of 65 the lever 74 from that mounted on the ful-

crum 75 is connected by a link 76 to one end of a bracket rod 77, which is rigidly fixed, as at 78, to the said rod 56, heretofore described.

When the steam pressure of the boiler acting under the diaphragm 46 is just balanced by the weights 52 and 53, acting through the lever 50, the valve heads 64 and 65 close the ports 62 and 63 leading to the top and bottom of the cylinder 54. Should the boiler pressure exceed the action of the weights 52 and 53, the diaphragm 46 will be pushed upward and the push rod 49 will raise the lever 50, causing the rod 70 to raise the link 71, elevating the end 72, and lifting the valve 80 stem 66 so that the valve heads 64 and 65 make connection for the fluid under pressure from the pipe 67 to pass through the port 62 and act on the upper side of the piston 55, while the port 63 allows the fluid in the 85 cylinder 54 beneath the piston 55 to escape through port 63 to the vent pipe 69, whereupon piston 55 and piston rod 56 and bracket 77 move downward. This motion is communicated by the link 76 to the lever 74, pivoted at 75 and causing the end 73 to be raised. The link 71 will move about the joint 70 as a pivot, lowering the end 72, and actuating the valve stem 66 and valve heads 64 and 65. The piston 55 will continue to 90 descend until the valve heads 64 and 65 have closed the ports 62 and 63, under which condition the piston will remain stationary. The movement of the piston 55 and piston rod 56 is communicated by the flexible connection or chain 57 to the valve 43 through the lever 44 connected at the point 59. Downward movement of the piston 55 raises the lever 44, moving the valve 43 toward its 95 closed position, and reducing the speed of 100 the blower engine 40 and the blower 37.

If the steam pressure acting under the diaphragm 46 is less than the action of the weights 52 and 53, acting through the lever 50, the lever 50 will be lowered and the reverse action from that above described will take place and the piston 55 will move upward, and through its connections will lower the lever 44, moving the port of the valve 42 toward its open position, increasing the 110 supply of steam to the blower engine 40, thereby increasing the speed of the engine and blower, and increasing the amount of air fed to the furnace.

The combined function of the damper regulating means heretofore described, and the blower engine speed controlling means heretofore described, is to establish and maintain a uniform steam pressure in the boiler for varying loads, and a uniform pressure 115 of furnace gases in the furnace for varying rates of combustion in the furnace.

This operation broadly is the subject matter of applicant's prior Patents 817,438, April 10, 1906; and 826,349, July 17, 1906. 120

I will now proceed to describe my improved method and means for controlling the rate of feed of the fuel supplied to the furnace constituting my present invention.

5 In the present embodiment this means consists of a method and mechanism for automatically varying the rate of feed of the stoker in accordance with the amount of draft supplied, or in accordance with the 10 thickness or resistance of the fuel bed, and is shown and hereinafter described as controlling and varying the speed of the stoker driving engine 9 to thereby vary the rate at which the fuel is fed to the furnace by 15 the stoker 3. 79 is a governor valve casing connected by a pipe 80 to the engine, and also connected by a pipe 81 to the steam pipe 41, communication between said pipes 81 and 80 being controlled by a valve 82, coöperating 20 with a valve seat 83 in said valve casing. The valve 82 is mounted on a valve stem 84, extending above the valve casing and surrounded by a sleeve 85, which is slideable longitudinally on said stem under the influence of the governor balls 86 fulcrumed, as at 87, on the frame 88 of the machine. Mounted below the said sleeve 85, surrounding the valve stem and exerting its force against the said frame and the lower end of 25 30 35 40 45 50 55 60 65 70 75 80 85 90 95 100 105 110 115 120 125 130 said sleeve is a spring 89, and a second spring 90 also surrounds said stem and is arranged above said sleeve, and abuts the upper end of said sleeve and the lower face of an abutment 91 rigidly mounted on the upper end of the valve stem and carrying a rack 92 meshing with a rack segment 93 carried on one end of a lever 94. The lever 94 is fulcrumed as at 95 on a frame 96, which is fastened on the upper end of the sleeve 85 and moves therewith. The arrangement is such that when the lever 94 is moved upward to cause the rack 92 to exert a downward force on the valve stem 84, the valve stem is lowered in proportion to the upward movement of the lever 94, causing less steam to be admitted to engine 9 from pipe 81 through the valve 79 due to the decreased clearance between valve seat 83 and valve 82. This will cause engine 9 to slow down to some lesser speed, and the balls 86 will move inward due to the decreased centrifugal force acting upon them (it being understood that the governor ball's support 88 is rotated by suitable driving connection, for example, a belt or chain connecting the governor support with the driving shaft of the engine through a pulley 86^a, on shaft 86^b, connected by bevel gearing 88^a to said governor support). The amount of this inward movement of the balls 86 depends upon the centrifugal force exerted upon them by the desired reduced speed of engine 9 governed by the upward position of lever 94. The balls 86 will now 85 slightly move inward or outward slightly raising or lowering sleeve 85 and part 96, causing valve stem 84 to slightly rise or lower with part 96 by means of rack 92 and segmental rack 93, and slightly varying the opening between valve 82 and seat 83 to 70 keep speed of engine 9 constant, as engine 9 varies slightly in its speed due to its variable load.

If the lever 94 is moved downward, the reverse action to that above described will 75 take place and the piston 84 will be raised admitting more steam to engine 9, and the balls 86 by their variation of position will keep engine 9 at an increased but constant speed by varying the amount of steam supplied to meet the requirements of the load on engine 9. Spring 89 is to keep sleeve 85 in close contact with governor ball arms and acts in opposition to centrifugal force on the balls, and spring 90 is to take up any lost 85 motion between rack 92 and segment 93 on the lever arm 94.

I will now describe an automatic means for shifting the lever 94 in order to operate the valve to increase or decrease the steam 90 fed to the stoker engine in accordance with the position of the flue damper 11, or the mechanism for operating the latter, the arrangement being such that as the damper is closed the speed of the stoker engine is reduced, and when the damper is moved toward open position the speed of the stoker engine is increased. This means may include adjustable mechanism for insuring the operation of the valve in proper relation to 95 the movements of the damper, or the variation of the speed of the blower or air supply. In order to accomplish this purpose the lever 94 may be connected by any suitable means to either the damper or its operating 100 mechanism for accomplishing the desired result. In the embodiment shown I provide a rotary element 97 mounted on a shaft 98, arranged in suitable bearings, (not shown), said rotary element carrying inner and outer 105 concentric plates 99, 100, connected to said member by bolts 101 and spaced from each other by spacing sleeves 102, mounted on said bolts between said plates. These plates are provided with alining radial slots 103, 110 in which are arranged radially adjustable abutments, preferably consisting of bolts 105, carrying spacing sleeves 106 located between said bolts and fastening nuts 107 threaded on the outer ends of said bolts, 115 said bolts serving to clamp the abutments rigidly in position, and also as abutments to coöperate with the lever 94, as will be presently described.

The member 97 is provided with a circumferential groove 108, about which is wound a flexible connection or chain 109, having at its free depending end a weight 110, and at its intermediate portion carried over guide rollers 111 and connected at its free 130

end to the piston 15, as at 112, the arrangement being such that when the piston 15 is raised the flexible connection is slackened and the weight 110 serves to cause the flexible connection to rotate the member 97, while the downward movement of the piston 15 serves, through said flexible connection, to rotate the member 97 against the force of the weight 110. By the use of the adjustable 5 abutments constituted by the nuts 107 I am able to insure such movement of the lever 94 as will cause the valve 82 to properly control the speed of the stoker engine in accordance with definite positions of the 10 damper, which in turn is controlled longitudinally by the speed of the blower through the medium of the furnace gas pressure. In order to properly position the abutments the blower is operated at say one-quarter its 15 normal speed. The damper, through the action of the regulator 28, will assume a position to maintain the desired pressure of furnace gases over the fire. The lever 94 is then adjusted by hand until the stoker 20 speed gives a rate of feed of fuel which will maintain a fire of the desired thickness or resistance. One of the adjustable abutments 107 is then moved through one of the radial slots 103 until it comes in contact 25 with the under side of the lever 94. The nut 107 is then screwed up, holding the abutment rigidly in this position in the slot, so that whenever the radial member 97 is 30 in this particular position, corresponding to one-quarter speed of the blower, and there is a normal fuel bed in the furnace, this fuel bed will be maintained automatically by the rate of feed of fuel. Similarly the blower 35 is operated at other speeds and the expanding position of the abutments fixed to give the desired rate of fuel feed desired for each 40 speed of the blower, for example as shown in Fig. 4 of the drawings. The rotating member 97 could manifestly be connected to 45 the flexible connection or chain 57 and be controlled in accordance with the variations of the blower speed, which latter is controlled directly by the steam pressure (see Fig. 7). The advantage, however, of varying 50 the rate of fuel feed in accordance with the movement of the flue damper when controlled by the regulator 28, is that in addition to varying the rate of fuel feed in accordance with the variations of blower 55 speed, the fuel feed is varied inversely in accordance with the resistance or thickness of the bed of fuel, so that if for any reason due to physical differences in the coal supplied to the stoker the resistance of the fuel bed 60 is decreased or increased, the relation of the speed of the stoker and the feed of fuel to the speed of blower, or supply of air, is increased or decreased.

It will be understood that my invention is

not limited to its use and combination with 65 an apparatus in which the speed of the blower is varied in order to vary the supply of air to the furnace, as, for example, an equivalent would be to operate the blower at a constant speed and suitable means be 70 provided for varying the amount of air passing to the furnace, for instance, by means of a controllable damper in the air duct.

I also desire it understood that the invention 75 is not limited to feeding means for any specific form of fuel, but includes in its scope means for feeding solid, pulverized, or fluid fuel.

What I claim and desire to secure by Letters Patent of the United States is—

1. The method of regulating furnaces which consists in maintaining in the furnace chamber a substantially uniform pressure under varying rates of combustion, and in 85 regulating the resistance of the fuel bed to bear any desired relation to the rate of combustion by controlling the rate of feed of fuel in accordance with variations in the means for maintaining in the furnace a sub- 90 substantially uniform pressure.

2. The method of regulating furnaces which consists in maintaining in the furnace chamber a substantially uniform pressure under varying rates of combustion, and in 95 automatically regulating the resistance of the fuel bed to bear any desired relation to the rate of combustion by controlling the rate of feed of fuel in accordance with variations in the means for maintaining in the 100 furnace a substantially uniform pressure.

3. The method of regulating furnaces which consists in maintaining in the furnace chamber a substantially uniform pressure under varying rates of combustion, and in 105 regulating the resistance of the fuel bed to correspond to different rates of combustion by controlling the rate of feed of fuel in accordance with variations in said means for maintaining in the furnace a substantially 110 uniform pressure.

4. The method of regulating furnaces which consists in maintaining in the furnace chamber a substantially uniform pressure under varying rates of combustion, and in 115 automatically regulating the resistance of the fuel bed to correspond to different rates of combustion by controlling the rate of feed of fuel in accordance with variations in said means for maintaining in the furnace a sub- 120 substantially uniform pressure.

5. The method of regulating furnaces which consists in maintaining in the furnace chamber a substantially uniform pressure under varying rates of combustion, and in 125 regulating the rate of feed of fuel in accordance with variations in the means for maintaining in the furnace a substantially uni-

form pressure, and in such manner that the rate of feed of fuel will vary inversely as to variation in relation of fuel bed resistance to rate of air supply, and directly as to the rate of air supply.

6. The method of regulating furnaces which consists in maintaining in the furnace chamber a substantially uniform pressure under varying rates of combustion, and in 10 automatically regulating the rate of feed of fuel in accordance with variations in the means for maintaining in the furnace a substantially uniform pressure, and in such manner that the rate of feed of fuel will 15 vary inversely as to variation in relation of fuel bed resistance to rate of air supply, and directly as to the rate of air supply.

7. The method of regulating furnaces which consists in maintaining in the furnace 20 chamber a substantially uniform pressure under varying rates of combustion, and in regulating the rate of feed of fuel in accordance with variation in the means for maintaining uniform pressure under varying 25 rates of combustion, so that the rate of feed of fuel will vary inversely as the resistance of the fuel bed, and directly as the rate of supply of air to the furnace.

8. The method of regulating furnaces 30 which consists in maintaining in the furnace chamber a substantially uniform pressure under varying rates of combustion, and in automatically regulating the rate of feed of fuel in accordance with variation in the 35 means for maintaining uniform pressure under varying rates of combustion, so that the rate of feed of fuel will vary inversely as the resistance of the fuel bed, and directly as the rate of supply of air to the 40 furnace.

9. The method of operating boiler furnaces which consists in maintaining a substantially uniform furnace gas pressure for varying rates of combustion, and regulating 45 the rate of fuel feed in accordance with the rate of outflow of the furnace gases.

10. In a boiler furnace, air impelling means for supplying draft thereto, a stoker for feeding fuel to the furnace, regulating 50 means for maintaining the pressure of the furnace gases substantially uniform for varying rates of combustion, and means whereby the stoker is controlled by said regulating means.

55. 11. In a boiler furnace, means for feeding fuel thereto, regulating means for maintaining the pressure of the furnace gases substantially uniform for varying rates of combustion, and means whereby the fuel feeding means is controlled by said regulating 60 means.

12. In a boiler furnace, air impelling means for supplying draft thereto, a stoker for feeding fuel to the furnace, regulating

means for maintaining the pressure of fur- 65 nace gases substantially uniform for varying rates of combustion, and means whereby the speed of the stoker is controlled by said regulating means.

13. In a furnace, a stoker for feeding fuel thereto, a regulator acting in response to fluctuations of pressure of furnace gases to render said pressure uniform, and fuel feeding means for the furnace controlled by said regulator.

75 14. In a furnace, a stoker to feed fuel thereto, air impelling means for furnishing draft, means for controlling the air impelling means by the steam pressure of the boiler, means for controlling the stoker in 80 accordance with the variations of the air impelling means, and means for maintaining a substantially uniform gas pressure in the furnace for varying rates of combustion, which last named means also varies the relative speed of the stoker to that of the air impelling means.

15. In a furnace, in combination, a damper, means affected by the pressure of furnace gases for operating said damper, a 90 stoker, a motor for driving the stoker, a controller for the motor, and means for automatically operating the controller in accordance with positions of said damper.

16. In a furnace, in combination, means 95 for controlling the air supply to the furnace, a stoker, a motor for driving the stoker, a controller for the motor, a movable member having a variable connection with the controller, said member being operated by the 100 means for controlling the air supply.

17. In a furnace, in combination, a damper, means affected by the pressure of furnace gases for operating said damper, a 105 stoker, a motor for driving the stoker, a controller for the motor, a movable member having a variable engagement with said controller, and means for moving said member in accordance with positions of said damper.

18. In a furnace, in combination, a dam- 110 per, means affected by the pressure of furnace gases for operating said damper, a stoker, a motor for driving the stoker, a controller for the motor, a rotatable member having an abutment to engage and operate 115 the said controller, and means for rotating said rotatable member in accordance with positions of said damper.

19. In a furnace, in combination, a damper, means affected by the pressure of fur- 120 nace gases for operating said damper, a stoker, a motor for driving the stoker, a controller for the motor, a rotatable member having a plurality of radially adjustable abutments, to engage and operate the said 125 controller, and means for rotating said rotatable member in accordance with positions of said damper.

20. In a furnace, in combination, a damper, means affected by the pressure of furnace gases for operating said damper, a stoker, a motor for driving the stoker, a controller for the motor, a rotatable member for operating the controller, and a flexible connection connecting said damper and rotatable member whereby the controller is op-

erated in accordance with positions of said damper.

10

In testimony whereof I have hereunto signed my name in the presence of a subscribing witness.

EMBURY McLEAN.

Witness:

E. M. LOCKWOOD.
